UNITED STATES PATENT OFFICE.

FRANK L. EMERSON, OF OAKLAND, CALIFORNIA.

CENTRIFUGAL PUMP.

Application filed June 26, 1924. Serial No. 722,479.

To all whom it may concern:

Be it known that I, FRANK L. EMERSON, a citizen of the United States, and a resident of Oakland, county of Alameda, State 5 of California, have invented new and useful Improvements in Centrifugal Pumps, of which the following is a specification.

My invention is particularly adapted to centrifugal pumps of the vertical shaft type 10 and has for its object the positioning, securing in place and packing of such pumps, whereby the pump may be installed and operated between zones of different pressure and with the greatest facility.

Other objects will appear from the drawings and specification which follow.

These objects I attain by providing a cylindrical wall member, in combination with the well or well casing and mounting 20 the suction portion of the pump concentric within said wall member and I then provide a cup leather or other suitable packing between the said wall member and the suction element of the pump.

By referring to the accompanying drawings my invention will be made clear.

Fig. 1 shows a vertical type of centrifugal pump to which my invention has been applied.

Fig. 2 is similar to Fig. 1 except the packing is shown in a different position and enabling the use of a larger runner and diffusing casing.

Fig. 3 is a variation wherein the cylindrical casing member is set in the bottom of a well and no special discharge pipe is employed.

Throughout the figures similar numerals refer to identical parts.

A conventional deep well is indicated by the numeral 1, within which is mounted the discharge casing 2, the shaft tube 3 and the shaft 4. The shaft is driven by the motor 5 and is supported in bearings 6, 7, 8, and at 45 the bottom of the discharge pipe 2 is the collar 9 integral with or fixed with the cylindrical wall member 10.

A three stage centrifugal pump is here indicated as having the diffusion vanes 11 and an outward flaring collar 50 attached thereto, by which water is withdrawn through a suction pipe 15 and discharged upward in the direction of the arrow 16, into, through and out of the discharge pipe 2 at the outlet 17, thus providing a smooth channel for the pumped discharge.

The shaft journals and bearings may be lubricated through the pipe 18. The water is closed off from the shaft and bearings by the tube 3, thus providing an oiling compartment between the tube 3 and shaft 4 as indicated by the space 19.

The impellers 12, 13, 14, operate within the casing members 20, 21, 22, and these are threaded together and mounted between 21 and 22 is a cup leather packing 23 which latter frictionally engages the wall of the thimble 10 and because of the pressure in the discharge column 24 the cup leather is forced against the wall 10 effectually sealing the pressure compartment 24 from the suction 15.

In the variation shown in Fig. 2 the pump is mounted above the packing gland which is here shown in combination with the suction thimble 25. When the pump is built in this way the full diameter of the interior of the discharge pipe 2 may be employed for the reception of the assembled pump, the thimble 10 having an interior diameter of 80 less than the diameter of the assembled pump but in excess of the pump suction member 25. In this way the largest possible pump may be placed within the casing 2 and its suction and delivery sides sealed from each other by the packing 26 which in this instance is mounted on the member 25 and held in place with the collar 27 sealing the packing against the wall 10.

In the variation shown in Fig. 3, the pump is adapted to operate in the bottom of any conventional well without a discharge pipe but having mounted in its bottom the cylindrical wall member 30 against which bears the packing 31 held in clamped relation 95 between the pump casing elements 32, 33.

In each instance the wall member, against which the packing seals, is made with a tapering or flaring throat portion 40, enabling the assembled pump with its cup leather packing to be lowered into the well without damage to the cup leather, the cup leather telescoping within the exterior wall member only over a very short travel and there sealing the discharge from the suction 105 as soon as the pump starts to operate and simultaneously anchoring the pump in its assembled and operative position.

It will also be noted that in each instance 110 the pump hangs suspended on the shaft tube 3 which remains in tension. The shaft is also in tension due to the weight of the

rotating parts and the water load thereon.

Both the shaft and shaft tube being in tension therefore contributes to the maintenance of alignment of the shaft and its 5 bearings.

I claim:

1. A centrifugal pump comprising a discharge pipe, a cylindrical wall member of reduced diameter attached to said pipe, a 10 pump casing, a tube from which said casing is suspended, a driving shaft passing through said tube and an impeller on said shaft and within said casing.

2. The combination set forth in claim 1 15 and packing means between the casing and the wall member.

3. The combination set forth in claim 1 and a suction pipe connected with said casing and of less external diameter than said 20 casing and packing means between said suction pipe and said wall member.

4. The combination set forth in claim 1 and packing means between the casing and the wall member and an outward flaring 25 collar at the top of said casing providing a smooth discharge for pumped fluid.

5. The combination set forth in claim 1

and a suction pipe connected with said casing and of less external diameter than said 30 casing and packing means between said suction pipe and said wall member and an outward flaring collar at the top of said casing providing a smooth discharge path for pumped fluid.

6. The combination of a vertical shaft 35 centrifugal pump and a pump casing, a discharge column and a cylindrical wall member fixed to the lower end of said column and of reduced internal diameter, a packing means between said member and said 40 casing expandible under the pressure of the discharge whereby the discharge side and the suction side of the pump are divided.

7. The combination of a vertical shaft centrifugal pump and an enclosing casing and a suction thimble of less external diameter than said casing, a cylindrical wall member surrounding said thimble, packing means between the thimble and the said member constructed and adapted to expand under the pressure of discharge and thereby seal the discharge from the suction side of the pump.

FRANK L. EMERSON.
